CLAIM

The design for tripod leg lock, substantially as shown
and described.

DESCRIPTION

FIG. 1 is a top and left front perspective view of a
tripod leg lock showing my new design;

FIG. 2 is a top plan view thereof as taken from line 2—2
of FIG. 1;

FIG. 3 is a bottom plan view thereof as taken from line
3—3 of FIG. 1;

FIG. 4 is a right side elevational view thereof;

FIG. 5 is a rear elevational view thereof;

FIG. 6 is a top and left front perspective view of a
modified form of my new design of FIGS. 1—5, the right
side being a mirror image thereto;

FIG. 7 is a rear elevational view thereof.
